(57) CLAIM

The ornamental design for a punch, as shown and described.

DESCRIPTION

FIG. 1 is a side elevation view of a punch showing my new design;

FIG. 2 is a opposite side elevation view thereof;

FIG. 3 is a front elevation view thereof;

FIG. 4 is a rear elevation view thereof;

FIG. 5 is a top plan view thereof;

FIG. 6 is a bottom plan view thereof; and,

FIG. 7 is a perspective view thereof.

The broken lines in FIG. 6 are included for the purpose of illustrating features on the bottom that form no part of the claimed design.
